UNITED STATES PATENT OFFICE.

HORACE M. FOULK, OF OSHKOSH, WISCONSIN.

RUNNING-GEAR FOR VEHICLES.

No. 833,379.

Specification of Letters Patent.

Patented Oct. 16, 1906.

Application filed May 25, 1905. Serial No. 262,251.

To all whom it may concern:

Be it known that I, HORACE M. FOULK, a citizen of the United States, residing at Oshkosh, in the county of Winnebago and State 5 of Wisconsin, have invented new and useful Improvements in Running-Gear for Vehicles, of which the following is a specification.

This invention relates to running-gears for vehicles, and more especially to that class of 10 vehicles known as platform spring-wagons.

The invention comprises the production of a bifurcated reach and a fifth-wheel integral with the spring-support.

The invention further comprises the production of a fifth-wheel the upper part of which is made integral and has formed thereon lugs for receiving spring-retaining means and a projecting lug or lip for guiding the lower portion of the fifth-wheel and a lower 15 portion made integral throughout and adapted to be secured to the front axle and be guided in its movement by the lug or lip formed on the upper portion of the fifth-wheel, as well as by the pivotal rivet acting 20 as a king-bolt.

The object in view is the production of a fifth-wheel and reach that may be easily assembled, of comparatively light weight, and of sufficient strength to withstand all the ordinary use to which it may be put.

Another object in view is the production of a bifurcated reach, a fifth-wheel cast in two pieces, and means for securing a spring to the upper part and the lower part to the 35 axle.

With these and other objects in view the invention comprises certain other novel constructions, combinations, and arrangements of parts, as will be hereinafter fully described 40 and claimed.

In the drawings, Figure 1 is a perspective view of a fifth-wheel and reach embodying the features of my invention, parts being broken away to better disclose the invention. 45 Fig. 2 is a top plan view of the fifth-wheel and reach embodying the features of my invention, certain parts being removed to better disclose the same. Fig. 3 is a section through Fig. 2 on line 2 2.

50 In the preferred embodiment of my invention 2, represents a rear axle, and 3 a front axle. The reach, as 4, is bifurcated at one end and is formed or spread so as to constitute arms 5 and 6, which are adapted to fit 55 upon the upper portion of the fifth-wheel. The fifth-wheel 7 is preferably cast in two

pieces, as 8 and 9. The upper portion 9 of the fifth-wheel has cast integral therewith a spring-receiving portion 10, which has formed thereon lugs 11 11 and 12 12 for receiving spring-securing members 13 14. Near each end of the portion 10 is preferably cast integral sockets 15 and 16, which are adapted to receive the ends of the reaches 5 and 6. The reaches 5 and 6 are also held in place upon the upper part of the fifth-wheel by means of bolts 17 and 18 and clamping means, as 19 and 20. The clamping means 19 and 20 pass through a cross-piece 21, which is formed integral with and rigidly attached to a stay 22, pivotally secured at 23 to a bifurcated member 24, which in turn is secured to a cross-bar 25, that is cast integral with the lower portion 8 of the fifth-wheel 7. The stay 22 is preferably secured 75 at 23 by means of the pivotal rivet mounted therein, but, as will be evident, may be held in place by means of a king-bolt passing through the cross-brace 26 down through the bifurcated portion 24 and stay 22. 80

An important feature of my invention is the sockets 15 and 16 and the reach-supporting portions 27 and 28, extending therefrom and formed integral therewith. As will be clearly seen from the drawings, the members 85 5 and 6 are placed upon the portions 27 and 28, upon which they find a solid support and to which they are rigidly secured. The portions 27 and 28 preferably extend a short distance beyond the fifth-wheel, so as to give 90 ample support and space for securing the members 5 and 6 in place.

The members 5 and 6 are bifurcations of the member 4, which extend to the rear in the usual manner. Secured to the member 4 95 at the point of bifurcation are braces 29 and 30 by clamps 31 and 32, as will be clearly seen in Fig. 2. The braces 29 and 30 extend on an arc of a circle to each end of the rear axle 2 and are secured in place by clips 11^a 100 11^a. As will be evident, these braces are used to impart stability to the reach.

Having thus described my invention, what I claim is—

1. In a device of the character described, 105 the combination with a front and a rear axle, a reach secured to said rear axle, said reach provided with diverging portions at its front end, said fifth-wheel provided with rearwardly-extending sockets, the bifurcated 110 portions of said reach seated within said sockets.

2. In a device of the character described, the combination with a front and a rear axle, a fifth-wheel carried by said front axle, a reach secured to said rear axle, said reach provided with bifurcated portions at one end, means securing said bifurcated portion to said fifth-wheel, a drop-stay fixedly secured at one end to the bifurcated portions of said reach, and means pivotally connecting the opposite end of said drop-stay to said axle.
3. In a device of the character described, the combination with a front and rear axle, a reach connecting said axles, a fifth-wheel carried by the front axle, of a bifurcated yoke fixedly secured to said front axle, and a drop-stay fixedly secured at one end to said reach and pivotally connected at its opposite end to said yoke.

4. In a device of the character described, the combination with a front and a rear axle, a reach provided with bifurcated portions, connecting said axles, a fifth-wheel carried by said front axle and connected to the bifurcated portions of said reach, a drop-stay connected to the bifurcated portions of said reach, a yoke pivotally connected to said stay, and means connecting said yoke to said front axle.

In testimony whereof I have hereunto set my hand in the presence of two subscribing witnesses.

HORACE M. FOULK.
